UNITED STATES PATENT OFFICE.

GEORGE PRIFOLD, OF LINWOOD, PENNSYLVANIA, ASSIGNOR TO THE CONGOLEUM COMPANY, OF PHILADELPHIA, PENNSYLVANIA, A CORPORATION OF PENNSYLVANIA.

PROCESS OF PRINTING FABRICS.

1,255,049.

Specification of Letters Patent. Patented Jan. 29, 1918.

No Drawing.

Application filed April 24, 1917. Serial No. 164,283.

To all whom it may concern:

Be it known that I, GEORGE PRIFOLD, a citizen of the United States, and a resident of Linwood, county of Delaware, State of Pennsylvania, have invented certain Improvements in Processes of Printing Fabrics, of which the following is a specification.

My invention relates to certain improvements in the process of printing designs upon woven fabrics, such as carpets, tapes-tries, &c.

One object of my invention is to improve the process of printing upon these mate-rials so that the color design will extend a considerable depth into the body of the fabric.

A further object of the invention is to use a dye, such as anilin, or its equivalent, as the coloring matter and to deposit it on the fabric with a vehicle, then removing the vehicle, leaving the coloring matter in the fabric.

The fabric after being woven is passed through a printing machine of the type illustrated in the patent granted to William H. Waldron on the sixth day of July, 1915, No. 1,145,821.

This machine consists essentially of a frame having a series of printing blocks and means for reciprocating said blocks and a series of pigment carriers, which are ar-ranged to reciprocate under the several printing blocks so as to supply the blocks with the coloring matter to be impressed upon the fabric. The pigment I use in the present instance is made of anilin colors and is mixed with starch, flour, or equivalent material, to give it sufficient body. The fabric is intermittently fed through the ma-chine and the impressions are made by the printing blocks, the number of printing blocks depending upon the design and the number of colors desired. The printed fabric passes from the machine and into a steam chamber having rollers at each end carrying bands at each side to which the fabric is clamped by any suitable clamping device.

The steam in the chamber causes the anilin colors to pass into the fibers so that the colors that were deposited on the sur-face of the fabric run and extend into the

body of the fibers. After the goods pass from the steam chamber they are festooned in a 55 drying chamber by looping the fibers over suitable bars, which are traversed on rails in the ordinary manner of festoon drying. This drying evaporates the moisture in the material so that the starch or flour become 60 dry, leaving the anilin colors in the fibers. In order to remove the starch or flour, or like material, that is used to carry the anilin dyes, I pass the fabric through a brushing machine 65 consisting of a series of abutments oppo-site brushes. There are a number of these brushes and at intervals there is a series of beaters consisting of a rotating drum having a series of bars thereon, which strike against the back of the fabric. The brushes act 70 against the face of the fabric, while the abutments support the back of the fabric. These brushes remove the dry flour or starch and the action of the beaters is to cause any particles of starch or flour that have gained 75 access to the body of the fabric to be re-moved therefrom and when the fabric passes through this brushing machine the anilin colors remain in the fabric and color the yarn to its full depth. After the fabric passes 80 the brushes, it is passed through a sizing de-vice which applies ordinary "size" to its back. This sizing device consists of a trough and a series of transfer rollers, but other forms of sizing devices may be used 85 without departing from the essential fea-tures of the invention. After the sizing has become dry, the printed fabric is in a fin-ished condition.

By the above process, I am enabled to 90 print elaborate designs and to cause the dye to penetrate the full depth of the fabric so that the entire surface of the fabric has the same appearance as a fabric where the strands are dyed prior to being woven. 95

More elaborate designs can be made by my improved process than by present methods of printing fabrics and the cost of the process of printing is considerably re-duced.

Although I have described the use of starch and flour as a carrier for the coloring matter and although I have described anilin colors as used, it will be understood that other vehicles may be used which can be 105 converted into powder and removed by

brushing or any equivalent of the anilin colors may also be used without departing from the essential features of the invention.

5. I claim:

1. The process herein described of printing woven fabrics, said process consisting in mixing a color capable of dyeing a fabric and a vehicle capable of being dried and 10 dusted out of the fabric, printing the fabric with said color, then subjecting the printed fabric to heat and moisture so as to cause the color material to enter the fabric, then drying the fabric so as to reduce the vehicle 15 to a solid, then removing the vehicle in the form of dust, leaving the coloring in the fabric.
2. The process herein described of printing woven fabrics, said process consisting in 20 mixing a color capable of dyeing the fabric and a vehicle capable of being dried and dusted out of the fabric, printing the fabric with said color, then subjecting the printed fabric to steam so as to cause the coloring matter to enter the body of the fabric, then 25 drying the fabric so as to reduce the vehicle to a solid, then brushing out the vehicle in

the form of dust, leaving the color in the fabric.

3. The process herein described of printing woven fabrics, said process consisting in printing a surface of the fabric with the color carried by a vehicle of starchy material, then subjecting the printed fabric to the action of steam so as to cause the coloring matter to travel into the fiber of the fabric, then drying the fabric so as to solidify the starch, and finally subjecting the fabric to a beating and brushing action so as to remove the starch and flour, leaving 40 the coloring matter in the fabric.

4. The process herein described of printing woven fabrics, said process consisting in printing the fabric with a composition consisting of an anilin color and a starchy 45 vehicle, subjecting the fabric to the action of moisture and heat to cause the anilin colors to penetrate the fabric, then drying the fabric to solidify the vehicle, then removing the vehicle from the fabric, leaving the 50 anilin color therein, and then sizing the back of the fabric.

In witness whereof I affix my signature.
GEORGE PRIFOLD.
